INDICATOR

Miles A. McLennan, Palmyra, N. J., assignor, by
mesne assignments, to Radio Corporation of
America, New York, N. Y., a corporation of
Delaware

Application October 26, 1934, Serial No. 750,053

3 Claims. (Cl. 172—245)

This invention relates to indicators, and more particularly to a device utilizing a cathode ray tube for forming an image on the screen thereof, the position of the image along the arc of a circle 5 being rendered indicative of some relationship between two existing conditions.

If, for example, two sources of alternating current are to be applied, one to the deflecting circuits of the cathode ray tube, and the other to 10 the focusing and accelerating anodes which project an electron beam against the fluorescent screen of the cathode ray tube, then my invention lends itself advantageously to the indication of phase relationship between these two sources 15 of alternating current.

One application of my invention is illustrated in its use as part of a compass system. The particular details of the compass system, other than as brought out in the instant specification and as 20 claimed herein, were invented by William A. Tolson, and disclosed in copending application Serial No. 750,631, filed October 30, 1934. The utility of my invention, however, may well be illustrated in connection with an earth inductor compass, 25 and it will be seen from the ensuing disclosure that my invention has many other applications, such as for radio beacons and for analyzing electric wave relationships in a variety of different circuits.

30 Accordingly, it is an object of my invention to provide an indicator of the cathode ray tube type in which a phase relationship between two existing alternating currents may be evidenced by the location of a light spot on the fluorescent screen 35 of the cathode ray tube.

Other objects and advantages of my invention include the provision of a device of the character mentioned in which the potentials for exciting the anodes are supplied directly from an amplifier 40 which furnishes a voltage wave of desired amplitude, periodicity and wave form.

Still further objects and advantages of my invention will become apparent upon reading the following detailed description in view of the accompanying drawing, in which the sole figure 45 thereof represents diagrammatically one embodiment in association with an inductor compass system.

As is well known in the art, a cathode ray tube 50 provides means for making an indication without involving the use of any rotating masses or other elements having appreciable inertia. The directive control of an electron beam within the cathode ray tube is usually accomplished by deflecting circuits which may be either of the magnetic or

the electrostatic type. If magnets are used, the coils thereof are disposed in pairs about the stem of the tube, one pair being at right angles to the other pair. If electrostatic plates are used in the deflecting circuits, then one pair of plates in one of the circuits is disposed at right angles to the pair in the other of the circuits. The electrostatic plates may be disposed either within or externally of the envelope of the cathode ray tube. 5

Referring to the drawing, I show the cathode ray tube 1 having magnetic deflecting coils 2 and 3 and having a focusing anode 4 as well as an accelerating anode 5. The screen end 6 is coated internally with a suitable fluorescent material. The tube is also provided with the usual cathode 15 7, which may, if desired, be indirectly heated as by means of the filament 8. The control electrode 9 is not in all cases essential, but it has been shown for convenience in regulating the intensity of the light spot to be formed on the fluorescent 20 screen through the action of the focused electron beam. If a control electrode 9 is provided, it may be suitably biased as by means of a connection thereto from the potentiometer 10 disposed across the terminals of a battery 11 or other source of 25 potential. Connections are made, as shown, with the grounded cathode 7.

The peculiar manner of exciting the anodes of this cathode ray tube according to my invention may perhaps be best illustrated by its use in connection with an earth inductor compass. Such a compass may, for example, include a coil 12 which is rotated in the earth's magnetic field. The rotation may be produced as by means of a small synchronous motor 13, the power for which may 30 be derived from any suitable alternating current source such as that shown at 14. This source may also be used, if desired, for exciting the deflecting circuits which are herein represented by magnetic coils 2 and 3. It is necessary that the 35 rotating field produced by the deflecting circuits should be kept in synchronism (though it varies in phase) with respect to the alternating current generated by the coil 12. The phase variation results from any variable orientation of the field of 40 the synchronous motor 13, such as produced when changing the course of the vessel on which the compass is carried. Furthermore, it is apparent that the coil 12 will generate one cycle of current 45 during one revolution, and that during the same time the deflecting circuits 2—2 and 3—3 will produce substantially one revolution of the magnetic field for controlling the direction of the electron beam in the cathode ray tube. 50

In order to provide a 90° phase displacement 55

between the current in coils 2 in reference to the current in coils 3, I introduce in the deflecting circuits in the one case a suitable resistor 15 and in the other case a capacitor 16. The resistive and capacitive values respectively are so chosen as to produce the desired 90° phase displacement. If a two-phase source of alternating current were available, it could, of course, be applied to the coils 2 and 3 in an obvious manner.

Because the synchronous motor 13 and the deflecting coils 2 and 3 are operated from a common source 14, it will be clear that synchronism is automatically maintained between the deflecting circuits and the rotations of the inductor coil 12. If the apparatus is carried on a moving vessel or on aircraft, then it is possible to make use of the phase coordination between the coil 12 and the deflecting circuits and thereby to indicate the direction in which the vessel or aircraft

may be headed.

The earth's magnetism induces a small alternating current in the coil 12, the frequency of the current being dependent upon the speed of rotation of the coil. One complete revolution of the coil generates one complete cycle of alternating current. By means of collector rings 17 and brushes 18 this current may be taken off and applied, say, across the grid and cathode leads of an amplifier tube 19. The grid 20 may, if desired, be suitably biased by means of the battery 21. Anode and screen grid potentials may be supplied from the source 22. The amplifier tube 19 may then be caused to function in the usual manner. More than one stage of amplification may be provided, if desired.

The intercoupling between stages may be either by means of transformers or by the usual form of resistance coupling, as is well known in the art. In this instance I have illustrated a suitable network comprising the electron tubes 19, 23 and 31, each of which serves a different purpose. The tube 23 normally draws very little current. One way of producing this result is to introduce between the cathode 24 and ground a high resistor 25, say, of the order of one megohm. This resistor is preferably shunted by a capacitor 26 permitting momentary currents of larger amplitude to flow. The grid circuit includes a resistor 27 and is coupled by means of a capacitor 28 to the output circuit of the tube 19.

The tube 19 provides substantially linear amplification of a sine wave current. When a maximum voltage is developed on the anode 30 a positive wave peak will then be applied across the capacitor 28 to the grid 29 which raises its potential just above the cut-off point due to the fact that this grid is normally very negatively biased by the resistors 25 and 21. A very sharply peaked impulse is, therefore, transmitted by the tube 23, this impulse being developed into a space current of suitable amplitude (aided by the low impedance of the capacitor 26) for suddenly lowering the plate potential and biasing the grid 31 of the tube 31 below its cut-off point.

Normally, the grid 31 may be so biased that a current of suitable amplitude will flow in the tube 31, thereby developing a more or less saturated magnetic flux in the core of the transformer 32. If the tube 31 becomes suddenly blocked, as when its grid momentarily goes negative, it will be seen that the stored energy in the transformer 32 must be dissipated through its secondary winding 33. It is possible in this manner to develop a very high potential such as is suitable for impressing upon the anodes of a cathode ray tube,

As a means to this end I have indicated the secondary winding 33 having one terminal thereof connected to ground and the other terminal connected to the accelerating anode 5. A lesser potential may be applied to the focusing anode 4 through a circuit which includes a tap 34 on the potentiometer 35, the latter being disposed across the terminals of the secondary winding 33.

In the operation of my invention the original sine wave generated by the coil 12 is translated by the tube 23 into discrete impulses which may be made steep-sided and of very short duration. It is only when these impulses occur that voltages will be developed on the anodes of the cathode ray tube. Hence it is possible to very sharply define the position of a luminous spot to be displayed on the fluorescent screen 6. While the deflecting circuits 2 and 3 may be functioning continuously, there is no electron beam to be projected upon the screen 6 until impulses are impressed upon the anodes 4 and 5. It is found, however, that the action of the focusing and accelerating anodes brings the light spot to its position of maximum intensity somewhere along the arc of a circle. This circle is preferably concentric with the screen 6 and conveniently near the periphery thereof. The spot seems to develop gradually along an arcuate path starting from the edge of the screen. When the peak of the impulse passes, the spot fades out as it departs from the point of focus along another arcuate path toward the edge of the screen. The converging of these paths of approach and departure provides a desirable pattern for the image of the light spot, in that the point of convergence is very clearly defined. The angle subtended between the paths of approach and departure may be made quite sharp, if so desired, by merely providing suitable electrical constants in the design of the transformer 32.

A suitable scale 36 may be printed on the glass of the screen so as to provide reference markings for any desired indication, whether the device is used as a compass, as a radio beacon, or merely for indicating phase angles between two alternating currents.

In the embodiment of my invention as shown it is apparent that the directional effect of the earth's magnetism produces an alternating current in the rotating coil 12 and the peaks of this current of one polarity are amplified and translated into voltage impulses of considerable magnitude to be applied to the anodes of the cathode ray tube. The synchronous motor 13 is of that type wherein its armature makes one revolution during a single cycle of current from the source 14. Since the mounting of the entire apparatus may be fixed in relation to the aircraft or vessel in which it is carried, and since the phase angle between the source of alternating current 14 and the alternating current generated in the coil 12 will vary with the orientation of the vessel, it is clear that the light spot appearing on the screen of the cathode ray tube will also be varied in its position on the circular scale. Thus the direction in which the vessel is headed may be indicated.

Other applications of my invention will readily occur to those skilled in the art. Its use is by no means limited to a compass, since there is a considerable demand for an indicator having inertialess elements, particularly in electrical research work, as well as in other fields of endeavor and for commercial apparatus. I do not intend, therefore, to be limited in the carrying out of my invention other than as is necessitated by the

prior art and by the spirit and scope of the appended claims.

I claim as my invention:

1. In a device for indicating the phase angle between two wave trains of like frequency; a cathode ray tube having deflecting circuits, an anode and a fluorescent screen; means responsive to the action of one of said wave trains and including said deflecting circuits for rotating the 5 ray of said cathode ray tube in a circular path substantially concentric with said screen; an amplifier for amplifying currents derived from the other of said wave trains; a thermionic tube normally biased to cut-off for amplifying the peaks 10 of positive impulses applied to its input circuit; means coupling said amplifier and said thermionic tube; a second amplifier whose output circuit includes an iron core inductor which is normally saturated by the currents normally flowing in 15 said output circuit; means including a coupling between said thermionic tube and said second amplifier for suddenly dissipating said saturation effects to generate a high potential; and connections between said inductor and said anode so 20 that said high potential applies the sole source of anode potential for focusing said cathode ray on said screen in accordance with the phase angle 25 between the two trains.
2. In a device for indicating the phase angle between two alternating currents of like frequency; a cathode ray tube having deflecting circuits, a focusing anode, and a fluorescent screen; means responsive to the action of one of said 30

alternating currents and including said deflecting circuits for rotating the ray of said cathode ray tube in a circular path substantially concentric with said screen; a thermionic tube normally biased to cut-off for amplifying the peaks of 5 positive cycles of the other of said alternating currents; an amplifier tube whose output circuit includes an iron core transformer which is normally saturated by the currents normally flowing in 10 said output circuit; means including a coupling between said thermionic tube and said amplifier for suddenly dissipating said saturation effects to generate a high uni-directional potential; and a connection between said transformer and said focusing anode which applies a sole 15 uni-directional potential for focusing said cathode ray on said screen in accordance with the phase angle between the two currents.

3. In a device for indicating the phase angle between two alternating currents the combination 20 of a cathode ray tube including deflecting means, a focusing electrode, and a fluorescent screen; means for applying the first of said alternating currents to said deflecting means to thereby rotate said ray in a substantially circular 25 path; and means including thermionic tubes for deriving positive impulses from the peaks of one phase of the second of said alternating currents and a saturation transformer across whose output terminals is established the sole anode potential 30 to focus said ray on said tube to indicate the relative phase angle between said currents.

MILES A. MCLENNAN.
